UNITED STATES PATENT OFFICE.

CLARENCE S. JOHNSTON, OF GLENDALE, MONTANA.

WAGON-TONGUE.

1,175,956.

Specification of Letters Patent. Patented Mar. 21, 1916.

Application filed September 1, 1914, Serial No. 859,680. Renewed August 7, 1915. Serial No. 44,288.

To all whom it may concern:

Be it known that I, CLARENCE S. JOHNSTON, a citizen of the United States, residing at Glendive, in the county of Dawson 5 and State of Montana, have invented a new and useful Wagon-Tongue, of which the following is a specification.

The present invention relates to improvements in wagon tongues, one object of the 10 present invention, being the provision of a tongue, the hounds of which are adjustably attached thereto so that the rear rigid ends may be moved to and from each other, and thus render the spacing thereof adjustable, 15 the forward connecting ends being resilient members to permit of the proper separation or movement of the hound members relatively to each other.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings Figure 1 is a top plan 30 view of the rear end of the tongue equipped with the present hounds. Fig. 2 is a bottom plan view thereof. Fig. 3 is a perspective view of one of the adjustable members showing the detailed construction thereof.

35 Referring to the drawings, the numeral 1 designates the tongue, whose rear end upon the upper face is reinforced by the metal plate 2 which is attached thereto in any desirable manner. Secured to the sides of the 40 tongue by means of the bolt 3 are the forward ends of the two resilient metal plates 4 and 4', the rear ends of which are connected to and carry the angle irons of rigid plates 5 and 5' which constitute the adjustable members of the hounds. Attached to 45 the flange 6 of each member 5 and 5' whose forward end is cut at an acute angle as at 7, while the rear end is cut at an obtuse angle as at 8, by means of the bolts 9-9' and 50 10-10', are the adjustable attaching arms 11-11' and 12-12', respectively. These arms are attached to have their slotted portions 13-13' and 14-14' overlap in clamp-

ing relation to each other, as clearly illustrated in Fig. 1.

55 Adapted to surround the inner ends of the tongue 1 to clamp the before mentioned slotted members in adjusted relation and upon the wearing plate 2, as illustrated in Fig. 1, are the two members 16 and 18, having the straddling portions or terminals 15 and 15', and 17 and 17', for entering the slots of such ends to clamp the same with the nuts as there illustrated. Thus the respective slotted plates 13 and 13' may be longitudinally adjusted relative to each other and thus produce the necessary adjustment of the hound members 5 and 5' relative to the adjacent portion of the tongue 1. By employing the plates 4, a certain amount of resiliency is permitted to accommodate the lateral adjustment of the hound members 5 and 5' without the necessity of dislodging or disconnecting the bolt 3. When preferred 70 the arms 11-11', 12 and 12' may be attached 75 with a single rivet instead of the bolts.

What is claimed is:

1. A wagon tongue, including a tongue proper, two rigid hound members, two resilient plates, one attached to the forward 80 end of each hound member, means for attaching the forward end of such resilient plates to opposite sides of the tongue, a plurality of adjustable arms carried by each hound member for co-operation, and means 85 for adjustably attaching the co-operating portions to the tongue, said hound members being L-shaped in cross section and the resilient members being attached to one flange thereof and extending the full length 90 thereof.

2. A wagon tongue, including a tongue proper, two rigid hound members, two resilient plates having their forward ends attached to opposite sides of the tongue intermediate of its ends while the rear ends are fixedly attached to the forward ends of the hounds, the combined length of one plate and one hound placing the rear end of the hound adjacent the rear end of the tongue 100 at one side thereof, two arms carried by each hound and projecting toward and upon one side of the tongue, the portions thereof adjacent the tongue being longitudinally slotted, the ends of the arms of the opposite 105 hounds being disposed in overlapping rela-

tion upon one side of the tongue, and two U-shaped bolts fitting astride of the tongue, the terminals of said U-shaped bolts being disposed through the slotted portions of the 5 coöperating arms of the hounds to rigidly secure the arms in adjusted relation to each other and the tongue.

In testimony that I claim the foregoing as my own, I have hereto affixed my signature in the presence of two witnesses.

CLARENCE S. JOHNSTON.
